UNITED STATES PATENT OFFICE.

ERNEST W. GATES, OF NEEDHAM, MASSACHUSETTS.

GAME DEVICE.

Application filed July 1, 1927. Serial No. 202,944.

The object of this invention is to provide a game device adapted to afford entertainment, and of educational value in that its operation simulates the action of a volcano 5 in eruption.

Of the accompanying drawings, forming a part of this specification,—

Figure 1 is a perspective view of a game device embodying the invention.

10 Figure 2 is a sectional view of the same.

Figure 3 is a view similar to Figure 2, showing means for illuminating the volcano crater when the device is operated to simulate an eruption.

15 The same reference characters indicate the same parts in all of the figures.

In the drawings, 12 designates a bed having a diversified surface including a protuberance 13, simulating a volcanic mountain, and terrain at the base of the protuberance.

20 The bed may be molded from any suitable plastic material adapted to solidify by drying, or it may be otherwise constructed. An upstanding curb 14 surrounds the bed and projects upwardly from the margin thereof, said curb being preferably a part of a box which includes a bottom 14^a. The summit of the protuberance 13 is provided with an 25 upwardly opening recess 15, surrounded by a wall which simulates a crater.

The device includes a plurality of loose balls 16, adapted to be assembled in the recess 15. 17 designates a ball-supporting 30 plunger which normally rests on the bottom of the recess and is formed to support the balls, as indicated by full lines in Figure 2. The plunger is movable vertically in the recess to cause the balls to roll outwardly over the recess wall, so that they are free to roll 35 downwardly on the protuberance 13. The bed is provided with a plurality of ball-receiving pockets 18, each designated by a value-indicating number 19 on the bed. Some 40 of the pockets may be formed in the protuberance, and others in the portion of the bed at the base of the protuberance. Balls rolling down the protuberance may lodge in the pockets, some of which are less freely accessible than others, the more inaccessible 45 pockets having higher values.

The plunger 17 is provided with a stem 21, extending downward through a guiding orifice 22, in the bed, the stem having a push member 23, at its lower end exposed in an

opening 24 in the bottom of the bed, and in the box bottom 14^a.

The game may be played by several players, each holding the device with its bottom horizontal and pressing a finger upward 60 against the push piece until the balls 16 are raised sufficiently to roll outward over the edge of the recess, and then downward on the protuberance.

The value-indicating numbers 19 of the 65 pockets in which balls are caused to lodge by each player, are added, the sum being the player's score.

The bed may be covered when not in use, by an inverted box 26, as indicated by dotted 70 lines in Figure 2.

The balls may be adapted to shine in the dark. For example, they may be hollow and of glass, and contain luminous material or composition, such as is used to render 75 watch hands and dial figures luminous.

Figure 3 shows a push member composed of a bell-crank lever 27, fulcrumed at 28 in a relatively large cavity 29 in the bottom of the bed. One arm of this lever is loosely 80 connected with the stem 21, and the other arm is loosely connected with a horizontal push rod 30, extending through an end of the bed, the arrangement being such that the plunger 17 may be raised by an inward 85 push on the rod 30, so that the device may be operated while resting on a horizontal support.

Figure 3 also shows, somewhat conventionally, an embodiment of means in which 90 the bell-crank lever 27 is included, for illuminating the crater when the plunger 17 is raised. An incandescent lamp 31 is mounted on a bracket 32, fixed to the bottom 14^a and is located in the cavity 29, in position to project its light upwardly into the recess 15, the latter being connected with the cavity 29 by a large opening 33. 34 designates a flash-light battery included in a normally open electric circuit, which includes 95 the lamp and a spring contact 35, carried by the bell-crank lever 27. The contact 35 is separated from the battery when the lever is in its normal position, the plunger 17 being lowered. When the lever 27 is moved to 100 raise the plunger, the contact 35 closes the circuit and the lamp is illuminated.

The plunger 17 may be adapted to permit 105 the projection of light through it. For example, the plunger may be composed of 110

woven wire, or perforated sheet metal, or of transparent or translucent material, such as celluloid or glass, which may be colored to color the projected light.

5. I claim:

1. A game device comprising a bed having a diversified surface including a protuberance simulating a volcanic mountain, an upstanding curb surrounding the bed, 10 the summit of the protuberance being provided with an upwardly opening recess surrounded by a wall which simulates a crater, a plurality of loose balls adapted to be assembled in the recess, and a ball-supporting 15 plunger formed to support said balls within the recess, and movable vertically therein to cause the balls to roll outwardly over the recess wall and upon the protuberance, the bed being provided with numbered ball-re- 20 ceiving pockets in which rolling balls may lodge.

2. A game device as specified by claim 1,

the plunger being provided with a stem extending downwardly into a cavity in the bed, the device comprising also a push member 25 located in said cavity and connected with the stem, the push member being manually movable to raise the plunger.

3. A game device as specified by claim 1, the plunger being provided with a stem extending downwardly into a cavity in the bed, the device comprising also a bell-crank 30 lever fulcrumed in said cavity and connected with the stem, said lever constituting a plunger-raising push member, and a push 35 rod extending horizontally through an end of the bed and connected with the lever.

4. A game device as specified by claim 1, comprising also an electric lamp located in a cavity under the crater, and means for 40 lighting the lamp when the plunger is raised.

In testimony whereof I have affixed my signature.

ERNEST W. GATES.
